UNITED STATES PATENT OFFICE.

WALTER S. ROBERTS, OF EDGEWOOD PARK, PENNSYLVANIA, ASSIGNOR TO WESTINGHOUSE ELECTRIC & MANUFACTURING COMPANY, A CORPORATION OF PENNSYLVANIA.

ACCENTUATING DEVICE FOR CONTROLLERS

1,333,733.

Specification of Letters Patent. Patented Mar. 16, 1920.

Application filed September 7, 1917. Serial No. 190,148.

To all whom it may concern:

Be it known that I, WALTER S. ROBERTS, a citizen of the United States, and a resident of Edgewood Park, in the county of Allegheny and State of Pennsylvania, have invented a new and useful Improvement in Accentuating Devices for Controllers, of which the following is a specification.

My invention relates to controllers and particularly to the means for accentuating the various controller positions.

One object of my invention is to provide a device for accentuating the various positions of a controller that shall be simple and compact in construction and reliable, effective and positive in operation.

The accentuating devices of the controllers now in service embody star wheels and rollers resiliently held in engagement with the star wheels. The teeth formed in the periphery of the star wheel are so shaped, in accordance with the size of the coöperating roller, that only a small force serves to move the drum slightly and, in some cases, a small oscillatory movement of the controller may be effected without moving it from one position to another. In such accentuating devices, it is difficult to hold the controller drum in a fixed position and to have definitely marked controller positions.

In a controller constructed in accordance with my invention, the accentuating device is provided with means for positively marking the various controller positions and preventing any oscillatory movement of the controller drum.

The single figure of the accompanying drawing is a plan view of a controller provided with an accentuating device constructed in accordance with my invention.

Referring to the accompanying drawing, a controller embodies a stationary frame 2, a cover 3 attached thereto, and a shaft 4 having a control drum 5 and a star wheel 6 rigidly mounted thereon. The control drum 5 is provided with the usual contact segments 7 which selectively engage contact fingers 8.

A lever 9, which is disposed adjacent to the star wheel 6, is pivotally mounted on a projection 10 which extends from the frame 2. A triangular block 11 is pivotally mounted on the lever 9 near one end thereof,

in any convenient manner, and is adapted to engage any one of the spaces between adjacent teeth 12 of the star wheel 6. A spring 13 is attached to the opposite end of the lever 9 for maintaining the triangular block 11 in engagement with the star wheel.

Inasmuch as the triangular block 11 has straight sides and the teeth 12 of the star wheel are so formed as to provide angular spaces therebetween which fit such straight sides, it is apparent that the block 11, when in position between any two adjacent teeth 65 of the star wheel, will positively mark a controller position and prevent oscillation of the controller drum.

Modifications in the structure and arrangement and location of parts may be made within the spirit and scope of my invention and such modifications are intended to be covered by the appended claims.

I claim as my invention:

1. In a controller, a rotatably mounted 75 star wheel having angular recesses, and a block of polygonal shape adapted to be resiliently held in any one of the recesses of said star wheel for accentuating the various controller positions.

2. In a controller, a wheel having angular recesses in the periphery thereof, a pivotally mounted block of polygonal shape, and resilient means for holding said block in any one of the recesses of said wheel.

3. In a controller, a star wheel, a pivotally mounted block of triangular shape, and means for holding the block in contact with said star wheel.

4. In a controller, an accentuating device 90 embodying a star wheel having angular recesses, a pivotally mounted arm having a block of polygonal shape pivotally mounted near one end thereof and having two of its sides conforming to the sides of each of said recesses, and means for holding the block in engagement with the star wheel.

5. In a controller, a shaft having a contact drum and a star wheel mounted thereon, a lever pivotally mounted adjacent to the star wheel, a block of triangular shape pivotally mounted on said lever near one end thereof, and resilient means attached to said lever for maintaining the triangular block in engagement with the star wheel.

6. In a controller, means for accentuating

the various controller positions comprising a star wheel and a block having angular projections in engagement therewith.

7. In a controller, an accentuating cam having a plurality of angular recesses, and a member having a plurality of angular projections severally adapted to occupy any one of said recesses to accentuate the positions of said cam.

10 8. In a controller, a rotatable accentuating cam having a plurality of peripherally dis-

posed angular recesses, and a centrally, pivotally mounted member having the configuration of an equiangular polygon, the vertices of said polygon being severally adapted to be moved into any one of said recesses upon a forward or backward movement of said accentuating cam.

In testimony whereof, I have hereunto subscribed my name this 23rd day of August 20 1917.

W. S. ROBERTS.
